UNITED STATES PATENT OFFICE.

GEORGE E. CHAMBERLAIN, OF DECATUR, ILLINOIS.

BURR MILL.

Application filed November 25, 1921. Serial No. 517,474.

This invention relates to mills for grinding cereals of the type provided with upper and nether stones revolving one upon the other, and has for its object the provision 5 of a grinding mill of the class named, which shall be of improved construction and operation.

The invention is exemplified in the combination and arrangement of parts shown 10 in the accompanying drawings and described in the following specification, and it is more particularly pointed out in the appended claims.

In the drawings,

Fig. 1 is a vertical sectional view, showing one embodiment of the present invention.

Fig. 2 is a somewhat diagrammatic plan view showing a detail of construction.

Fig. 3 is a fragmentary vertical section showing the driver for the upper stone.

Fig. 4 is a section on line 4-4 of Fig. 3.

Fig. 5 is a vertical section of the footstep bearings of the main drive shaft.

Figs. 6, 7 and 8 are perspective views of parts of a driving support for the upper stone.

In mills as heretofore constructed, having a revolving stone driven by a vertical shaft 30 or spindle connected by belts or gearing with a source of power, there has been considerable loss of power due to side pulls on the bearings and the arrangements have been lacking in economy and convenience of 35 floor space.

In the present invention a driving motor is mounted directly on the mill spindle, thus providing a more compact arrangement and avoiding the friction loss due to side pulls.

A synchronous electric motor is preferably 40 used, since such a motor provides uniformity of speed which is desirable.

The mill parts are supported by a frame 10, as shown in Fig. 1, on the central lower portion of which there is carried a plate 11, in which a bearing support 12 is threaded. Within the support 12 there is mounted a roller footstep bearing having a self-aligning ball race 13 carried on a washer 14. A 45 plate 15 rests on a series of balls 16 traveling on the race 13. A stud 17 is formed on the lower end of the mill spindle 18 and the weight of the spindle and supported parts is transmitted through a flange 19 on the 50 shaft 18 to the supporting balls 16. A series

of balls 20 support the shaft against lateral movement.

The frame 10 supports the pole pieces 21 forming the field of an electric motor, the armature of which is shown at 22 secured 60 directly to the spindle 18. The coils 23 of the pole pieces are preferably made wider than usual to provide a field of sufficient extent to permit vertical adjustment of the armature 22 without displacing it from the field. Fan blades 23' may be carried by the armature 22 for the purpose of ventilation and cooling where desirable. Brushes 24 and slip rings 25 are provided for supplying current to the armature 22. A cover 70 plate 26 is supported on the upper face of the motor field frame and completely shields the motor from any moisture which might fall from the grinding stones or parts above the motor. The cover plate 26 carries a centrally disposed bearing 27 for the upper portion of the spindle 18, and a series of screws 28 are provided for shifting the plate 26 laterally for adjusting the bearing for the upper end of the spindle. The frame 10 75 above the cover plate 26 carries a bed 29 having a circular side wall 30, in which the lower grinding stone 31 is supported. The stone 31 may be adjustably located on the bed 29 by screws 32 extending upwardly 80 through the bottom of the bed and laterally adjustable screws 33 projecting through the side wall 30. When the stone 31 has been accurately placed the space about the stone is filled with cement, which firmly holds the 85 stone in place after it has set. The upper stone 35 is supported on the spindle 18 by means of a bail 36, shown more clearly in Figs. 3, 4 and 6. The bail 36 is provided with a tapered opening 37 in which the 90 cockeye 38 is seated. Laterally projecting arms 39 engage recesses in the stone 35 for supporting the stone. The ends of the arms 39 may be encased in bushings 40 to prevent injury to the stone. The cockeye 38 is carried by a ball and socket joint upon the cockhead 41, which is provided with a tapered seat in the supporting driver 42. The driver 42 fits over a reduced portion 43 on the spindle 18 and is secured to the spindle 100 by a pair of keys 44. Collars 45 are interposed between the lower end of the driver 42 and the shoulder 46 on the spindle 18. The opening for receiving the spindle 18 in the driver 42 is of sufficient depth to permit 105

110

lowering of the driver on the spindle if the collars 45 are removed. This will allow for lowering of the upper stone on the spindle 18 as the faces of the stones wear away.

5 The spindle itself is vertically adjustable, as will be explained, to provide for small vertical movements of the upper stone. Interposed between the supporting driver 42 and the bail 36 is an intermediate driver 10 47, Fig. 7, which is provided with arms 48 to engage openings 49 in the bail 36 and with openings 50 for receiving arms 51 on the supporting driver 42. In this way an efficient means is provided for supporting 15 the upper stone on the spindle 18 so that the stone is driven by the rotation of the spindle and yet permitted a limited universal movement to accommodate the driving faces of the stones to one another.

20 Closely fitted packing 51 surrounds the lower portion of the supporting driver 42 and is contained in a circular box or gland 52 cemented or otherwise secured to the lower stone 31, as shown in Fig. 3. A metallic 25 plate 53 covers the packing 51, and above the plate 53 is a wooden block 54 the upper face of which is flush with the upper face of the stone 51 and which wears away with the stone. This packing arrangement prevents 30 moisture or other substance from leaking down about the shaft 18 to interfere with the shaft bearing or motor. A housing 55 surrounds the upper stone and is provided with a hopper 56, through which grain is fed to the central opening in the upper stone from which it passes outwardly between the stones and is ground. A discharge chute 57 is provided at one side of the housing, and a sampling hand-hole 40 58 may be arranged above the chute 57 in the usual manner.

As shown in Figs. 1 and 2, the bearing support 12 is provided with a worm wheel 59, which meshes with a worm 60 carried 45 on the shaft 61. The shaft 61 is connected by beveled gearings 62 with a hand crank 63, by means of which the worm wheel 59 may be rotated to raise or lower the spindle 18 and the upper stone 35. For more convenient operation of the raising mechanism the shaft 61 is preferably provided with an electric motor 64 having a magnetic clutch 65 for connecting the motor with the shaft. The clutch and motor are preferably 50 arranged in series with one another in their electric circuit, so that when the circuit is closed for operating the motor the clutch will automatically connect the motor with the shaft and when the circuit is broken 60 for stopping the motor the clutch will automatically disconnect the motor and shaft, leaving the shaft free for rotation by the hand wheel 63. The motor 64 is reversible and a control such as a pair of push buttons 65 is provided by means of which it may

be operated in either direction to any desired extent. This means provides a convenient device for adjusting the height of the stones relative to one another and for raising the upper stone in case the supply 70 of grain to the mill is shut off or for any other reason that may occur in the operation of the mill.

I claim:

1. A mill having a pair of grinders arranged one above the other, a vertical spindle supporting one of said grinders, means for raising and lowering said spindle to adjust the grinder supported thereby relative to its companion grinder, and a motor for rotating said spindle, said motor having the armature thereof secured to said spindle for vertical movement therewith and having a stationary field in which said armature is moved when said spindle is adjusted vertically. 75

2. A grinding mill comprising a vertical spindle, a grinder supported by said spindle, an armature directly connected to said spindle for driving said grinder, a roller bearing for supporting said spindle, and means for raising and lowering said bearing and spindle to adjust said stone. 80

3. A grinding mill comprising a rotatable grinder, a direct connected motor positioned beneath said grinder for driving the same, means for collecting ground material discharged from said grinder, and means in addition to said collecting means interposed between said grinder and motor to intercept 100 moisture or other substances which might fall from said grinder onto said motor. 95

4. A mill comprising a rotatable grinder, an upright shaft for driving said grinder, means for collecting material discharged from said grinder, a motor directly connected with said shaft, packing surrounding said shaft to prevent moisture or other substance from gravitating around said shaft from said grinder, and a cover below said collecting means and interposed between 110 said motor and grinder. 105

5. A grinding mill comprising an upper and a lower grinder, an upright spindle for driving one of said grinders relative to the other, a motor directly connected with said spindle beneath said grinders, packing surrounding said spindle, and a cover interposed between said stones and said motor below said packing. 115 120

6. A mill comprising a lower stationary grinder, an upper rotary grinder, an upright spindle, a driver carried by said spindle, removable spacers interposed between said spindle and said driver to adjust the position of said driver on said spindle, a support for said upper grinder carried by said driver, and means interposed between said support and said driver for rotating said support while permitting move- 125 130

ment of said support relative to said driver to accommodate the faces of said stones to one another.

7. A mill comprising a lower stationary grinder, an upper rotary grinder, an upright spindle, a driver mounted on said spindle and having a cockhead carried thereby, a bail for supporting said grinders mounted on said cockhead, means for rotating said bail from said driver while permitting relative movement thereof, means for raising and lowering said spindle, and means for adjusting said driver relative to said spindle.
- 15 8. A mill having a pair of grinders arranged one above the other, a vertical

spindle supporting the upper grinder, means for raising and lowering said spindle to adjust the grinder supported thereby relative to its companion grinder, and a motor for 20 rotating said spindle, said motor having the armature thereof secured to said spindle for vertical movement therewith and having a stationary field structure in which said armature is moved when said spindle is adjusted vertically for the purpose of adjusting the grinders.

In testimony whereof I have signed my name to this specification on this 22nd day of November A. D. 1921.

GEORGE E. CHAMBERLAIN.
